UNITED STATES PATENT OFFICE.

STEVE URBAN, OF DAISYTOWN, PENNSYLVANIA.

DESIGN FOR A TOY.

52,903.

Specification for Design.

Patented Jan. 14, 1919.

Application filed September 6, 1918. Serial No. 252,977. Term of patent 7 years.

To all whom it may concern:

Be it known that I, STEVE URBAN, a subject of the King of Hungary, residing at Daisytown, in the county of Washington and State of Pennsylvania, have invented a new, original, and ornamental Design for Toys, of which the following is a specification, reference being had to the accompanying drawing, forming part thereof.

The figure is a perspective view of a toy, showing my new design.

I claim:

The ornamental design for a toy, as shown.

STEVE URBAN.

Witnesses:

L. L. BANE,
FRANK BORDASH.
